No. 874,546.

PATENTED DEC. 24, 1907.

W. H. SHAFER.
AERIAL LADDER.
APPLICATION FILED APR. 28, 1906.

UNITED STATES PATENT OFFICE.

WILLIAM H. SHAFER, OF CINCINNATI, OHIO.

AERIAL LADDER.

No. 874,546.

Specification of Letters Patent.

Patented Dec. 24, 1907.

Application filed April 28, 1906. Serial No. 814,161.

To all whom it may concern:

Be it known that I, WILLIAM H. SHAFER, a citizen of the United States, residing at Cincinnati, Ohio, have invented a new and useful Improvement in Aerial Ladders, of which the following is a specification.

My invention relates to aerial ladders of the extensible class mounted on a truck by means of a turn-table and adapted to the use 10 of firemen, and the objects of my improvement are to provide a device which may be actuated in its different movements by a single operator when standing on the ground; to provide a spring controlled mechanism 15 adapted to partially counterbalance the weight of the ladder in its adjustment to different vertical angles; to provide a spring controlled mechanism adapted to counterbalance the top ladder in its longitudinal adjustments; to provide means for moving and 20 maintaining the ladder in different vertical angles; and to combine durability and simplicity of construction with efficiency and facility of operation. These objects are obtained in the following described manner, 25 as illustrated in the accompanying drawings, in which:—

Figure 1, is a plan with parts broken away of an aerial ladder embodying my improvement; Fig. 2, a side elevation with parts broken away; Fig. 3, a longitudinal section on the line *a—a* of Fig. 4, with parts broken away; Fig. 4, a transverse vertical section on the respective lines *b—b* and *c—c*, of Figs. 2, 35 3 and 7; Fig. 5, a cross section of the turn table on the line *d—d* of Fig. 1; Fig. 6, an end elevation of the helical springs and contiguous fulcrums, and Fig. 7, an end elevation of a spiral spring with the windlass drum in section.

In the drawings, 1 represents the side rails of a truck of the usual construction whereon a turn table is mounted which consists of a stationary member 2 and a movable member 45 3. Said stationary member is formed with an annular flange 4 and with a plane upper surface which contains a series of circular concentric grooves. Partitions 5 are removably secured in said grooves to form 50 races or channels for anti-friction balls and to permit the plane surface to be reground when necessary. The movable member 3 is mounted to rotate on said balls and is provided on its inner edge with a depending gear 55 7 and on its outer edge with a depending rim

which encircles flange 4 and terminates thereunder in an inwardly turned annular lip 8. Said lip is formed with a plane upper surface in registration with the plane under surface of the flange and contains a concentric groove 60 wherein partition 9 is removably secured to form channels for anti-friction balls whereby said members are maintained parallel with each other. A short shaft 12 adapted at its outer end to detachably engage with a crank 65 is journaled on the under side of the stationary member 2 and provided with a pinion 13 which engages with gear 7 and serves to rotatively adjust the movable member in relation to said stationary member. 70

The main ladder 14 is provided with a top ladder 15 which is extensively secured thereon by means of the usual guide straps 16. It is also provided with heel brackets 17 wherein a transverse shaft 18 is securely fastened. 75 Said shaft is journaled on the movable member 3 of the turn table by means of bearing stands 19 and forms the pintle of the hinge whereon the ladder is movable in different vertical angles.

An operating shaft 21 adapted at each end to detachably engage with a crank and provided with bevel gears 22 and a miter gear 23 is journaled parallel with shaft 18 in bearings secured on member 3. An auxiliary operating shaft 24 provided with a crank bearing on its outer end and with a miter gear 25 in engagement with gear 23 is journaled on member 3 perpendicular to shaft 21. 85

Adjusting screws 26 threaded in respective 90 opposite directions are pivotally mounted on shaft 21 and each provided with a bevel gear 27 which engages with the corresponding gear 22 on said shaft. Nuts 28 pivotally secured to the side rails of the main ladder 95 by means of projecting brackets 29 are adjustably threaded on the respective adjusting screws.

By means of a crank attached to the end of shaft 24 or to either end of shaft 21 the 100 adjusting screws may be rotated simultaneously in opposite directions, whereby the ladder is moved and maintained in any desired vertical angle.

A plural number of spur gears 31 each 105 provided on one side with a lug or dog 32 are secured a short distance apart on shaft or pintle 18, and a corresponding number of fulcrum plates 33 are secured on member 3 of the turn table near said shaft and opposite 110

the respective dogs. A series of helical torsion springs 34 encircle shaft 18 with their respective ends engaging with corresponding dogs 32 and fulcrum plates 33.

5 Said springs 34 may be constructed to exert a torsional resistance, from near zero to near the limit of their strength, to shaft 18 in its movement to the extent of a quarter turn to approximately counter balance the weight 10 of the ladder and facilitate its adjustment to different vertical angles by a single operator.

Auxiliary shafts 35 are journaled equidistant from and parallel with shaft 18 on 15 member 3 by means of bearings 36. Each of said shafts is provided with a series of spur gears 37 in engagement with corresponding gears 31 and with helical torsional springs 38 similar to and arranged in the same manner as are the springs 34 on shaft 18 whose torsional resistance to said shaft they serve to reinforce. The number of torsional springs necessary to counterbalance ladders of different weights may thus be connected 25 to shaft 18. A hood 39 serves to cover and protect the spring mechanism mounted on shafts 18 and 35.

A windlass shaft 41 adapted at one end to detachably engage with a crank and provided with a spur gear 42 and with a longitudinal groove 43 is journaled in the hubs 44 of a stationary fulcrum drum 45 which is secured to the heel of the main ladder. A hollow windlass drum 46 provided with a spur 35 gear 47 encircles drum 45 and is mounted to turn on said hubs. A short auxiliary shaft 48 adapted at one end to detachably engage with a crank is journaled in a bearing on the heel of ladder 14 and provided with different sized spur gears 49 and 51 which engage with the respective gears 42 and 47 and provide differential speeds for drum 46. Sheave 52 secured on the upper portion of the main ladder carries a cable 53 which is 40 secured at its respective ends to the drum 46 and to the lower portion of the top ladder in the ordinary manner. A series of spiral torsion springs 54 encircle shaft 41 within drum 45 and are secured at their respective ends 45 to the periphery of said drum and within groove 43 to shaft 41 in such manner as to exert their torsional resistance on said shaft in unwinding the cable from drum 46 and serve to approximately counter balance the 50 weight of the top ladder when in a vertical position and permit a single operator to adjust it longitudinally with little exertion. Said springs 54 may be constructed to maintain an approximately uniform torsional resistance to the rotation of drum 46 in the 55 possible longitudinal adjustments of the top ladder, and any necessary number of said springs may be used to counter balance corresponding top ladders of different weight.

65 My improvement may be advantageously

applied to water towers or other similar devices without any material change in construction.

In operation, whatever may be the rotative position of the turn table, either the end 70 of shaft 24 or one of the ends of shaft 21 is accessible to the operator to move and maintain the ladder in different vertical angles with the assistance of the helical spring mechanism.

Shafts 41 and 48 provide different speeds whereby the operator, with the assistance of the spiral spring mechanism, may adjust the top ladder longitudinally.

Having fully described my improvement, 80 what I claim as my invention and desire to secure by Letters Patent of the United States is:—

1. An extensible member fulcrumed at a fixed point and provided with an actuating 85 windlass having in combination a stationary drum, a crank shaft journaled therein, a rotative cable drum mounted concentric therewith and inclosing the stationary drum, gears engaging the crank shaft therewith, and a 90 spring for yieldingly resisting the rotation of the shaft.

2. An extensible member provided with an actuating windlass having in combination a crank shaft, a rotative cable drum mounted 95 concentric therewith, a spring for yieldingly resisting the rotation of the shaft, and differential gears arranged to rotate the drum and shaft at different speeds.

3. The combination of an extensible member fulcrumed at a fixed point, a crank shaft and a cable drum journaled thereon, gears for rotating the drum and shaft at respective different speeds, and a spring arranged to yieldingly resist the movement of the drum 105 in relation to the shaft.

4. The combination of an extensible member fulcrumed at a fixed point, a drum journaled thereon, a cable actuated by the drum for extensibly adjusting the member, a crank 110 shaft journaled in the axial line of the drum, differential speed gears actuated thereby for driving the drum, and a spring arranged to yieldingly resist the difference in the speed of the shaft in relation to the drum.

5. The combination of a turn-table, a main shaft and a secondary shaft journaled thereon, gears connecting them together an extensible member secured to the main shaft and movable in a vertical plane, a series of 120 springs mounted on each of said shafts and arranged to collectively exert a yielding resistance to the movement of said shafts, by the descending movement of said member.

6. The combination of a turn-table, an extensible device movably supported thereon and consisting of a main member and a top member movable longitudinally in relation thereto, windlass and cable mechanism adapted to move and maintain said top 125 130

member in different positions of adjustments, and a series of springs arranged to exert a yielding resistance on the windlass to the tension of the cable.

5 7. The combination of a cable and a windlass, an extensible member adjustable longitudinally thereby, and a series of springs mounted on the windlass shaft and arranged to resist the pull of the cable thereon.

10 8. The combination of a main ladder, a cable and windlass mechanism mounted

thereon, a top ladder longitudinally adjustable on the main ladder thereby, and a series of springs arranged to exert a yielding resistance on the windlass to the tension of the 15 top cable, whereby the weight of the top ladder is approximately counterbalanced.

WILLIAM H. SHAFER.
